SLITTING AND REWINDING MACHINE.

1,350,064.

Specification of Letters Patent. Patented Aug. 17, 1920.

Application filed May 23, 1919. Serial No. 299,273.

To all whom it may concern:

Be it known that we, JAMES A. CAMERON and GUSTAF B. BIRCH, citizens of the United States, and residents of the borough of Brooklyn, in the city of New York, county of Kings, and State of New York, have invented certain new and useful Improvements in Slitting and Rewinding Machines, of which the following is a specification.

10 The present invention relates generally to slitting and rewinding machines, and more particularly to the type of machine employing surface rewinding drums.

In machines of this character it is customary to employ a front and a rear surface rewinding drum in spaced relation, above and intermediate which there is a displaceable rewinding shaft which latter supports the rewound material. The slotted sections of 15 material pass over one or both of the rewinding drums and thence to the rewinding shaft, the drums, by peripherally engaging the coils of material on the rewinding shaft, acting to wind the material. In some instances the winding of the material is facilitated by means of a slip friction drive connected to the rewinding shaft, and under some circumstances the rewinding shaft also 20 performs the function of a pressure roller.

25 This latter function is, however, usually performed by a "riding roller" engaging the upper surface of the coils, and this riding roller may or may not be driven. In some cases one of the surface rewinding drums also performs the function of a backing or 30 cutter roller against which a slitting element operates to cleave the material, but in some devices the cutter or backing roller is an element distinct and separate from the surface 35 rewinding drums. Also in some machines the slitting elements are of the "shear-cut" type consisting of rotary shears in overlapping relation and in such machines it is customary to have the slitting elements distinct 40 and separate from the rewinding means.

45 It has been the practice in machines of the types described to have the upper surface of rewinding drums and the lower surface of the rewound coils rotate away from the 50 front or operating side of the machine, and since slitting and other elements, requiring adjustment by the operator, are located adjacent to said front or operating side the

parts are necessarily more or less exposed with the result that, should the operator get 55 his hand or arm caught between the drums and the rewound material, the tendency will be to draw him into the machine and to crush or maim him.

The main object of this invention is to 60 obviate this dangerous condition, and the invention therefor consists in so arranging the parts that the upper surface of the drums and the lower surface of the rewound material travel in an outward direction, that 65 is: toward the front or operating side of the machine.

In the accompanying drawings the invention is disclosed in a concrete and preferred form in which—

70 Figure 1 is a view, in vertical cross section showing one form of surface rewinding machine embodying the invention and,

75 Fig. 2 is a more or less diagrammatic view indicating one form of transmission mechanism employed in such machine.

1 and 2 indicate respectively the front and rear surface rewinding drums rotatably mounted in spaced relation, above and intermediate which is a rewinding shaft 3 that 80 is automatically displaced as the coils increase in diameter in a manner well understood. 4 is a riding roller that may be employed in connection with the invention. A web 5 is led into the machine in any suitable 85 manner as over compensating roller 6 and tension roller 7 to guiding, cutting or backing roller 8 from whence it passes against surface of front drum 1 and up between the front and rear drums and thence to rewinding shaft 3. It will be seen that in this manner the rewinding drums may be so rotated that their upper surfaces rotate outwardly, *i. e.*, toward the front or operating side of machine at the left of Fig. 1. 95

100 Suitable means for effecting rotation of the parts in the proper direction may take many forms, but as here shown it is as follows: Power is applied to the shaft of rear rewinding drum 2, carrying a spur gear 9 meshing with an intermediate gear 10 on shaft 11, said gear 10 also meshing with gear 12 on front rewinding drum. Mounted on shaft 11 is a bevel gear 13 meshing with bevel gear 14 on upright shaft 15 from 105 which latter motion may be transferred to

riding roller by means of bevels 16 and 17; gear 16 having a sliding movement on 15 to compensate for the rise of the riding roller due to increase in diameter of the rewound material. Guiding roller 8 may also be positively rotated but in a direction opposite to that in which the drums turn, and this is accomplished by means of intermediate pinion 18 meshing with gear 10 on shaft 11 and with pinion 19 on end of guide roller 8. The direction of rotation of the various rollers is indicated by arrows in Fig. 1. In the present form of the invention roller 8 is a backing roller having a glass-head surface with which cooperates one or more score-cutters as 20. Said score cutter is rotatably mounted at 21 in a bearing 22 pivotally supported at 23, the bearing being controlled by spring 24 so that score cutter 20 is normally urged into engagement with backing roller 8. When, as in the present instance, the web is slit before it reaches the rewinding drum 1, it is essential that the web be controlled at all times and that the shortest possible distance be between the backing roller and the rewinding drum. It will be observed that roller 8 is very closely adjacent drum 1, but sufficient space is left to admit of the exterior of separator 25 in between the elements. This separator may simply be a rounded member bearing upon adjacent slotted edges and producing a slight momentary curve therein to snap any remaining fibers between said sections. Separator 25 is here shown as being carried by spring arm 26 adjustably carried on slide 27, said slide being in turn adjustably mounted on rail 28 and held in position by set screw 29. It will be observed that the parts adjacent the front or operating side of the machine are all exposed and readily accessible, and that, at the same time, no danger to the operator lurks in them.

We claim:

45 1. A rewinding machine comprising: a front and a rear surface rewinding drum in spaced relation, a displaceable rewinding shaft above and intermediate the rewinding drums, means for guiding flexible material over the surface of the front rewinding drum and up between the two drums to the rewinding shaft, and means for rotating the two drums in one and the same direction.

50 2. A rewinding machine comprising: a front and a rear surface rewinding drum in spaced relation, a displaceable rewinding shaft above and intermediate the rewinding drums, a guiding roller below the drums for guiding flexible material over the surface of the front rewinding drums and up between the two rewinding drums to the rewinding shaft, and driving means for rotating the two drums in one and the same

direction and for rotating the guiding roller in the opposite direction.

3. A slitting and rewinding machine comprising: a front and a rear surface rewinding drum in spaced relation, a displaceable rewinding shaft above and intermediate the rewinding drums, a backing roller below the rewinding drums for guiding slit sections of material over the surface of the first rewinding drum and up between the two rewinding drums to the rewinding shaft, driving means for rotating the two 75 drums in one and the same direction and for rotating the backing roller in the opposite direction, and a slitting element engaging with and frictionally driven by the backing roller.

4. A rewinding machine, having an exposed front or operating side, comprising: a front and a rear rewinding drum in spaced relation, a displaceable rewinding shaft above and intermediate said drums, means for so rotating the front and rear rewinding drums in one and the same direction that their upper surfaces and the lower surface of rewound material on the rewinding shaft move in a direction toward the front side of the machine, and means for guiding material over the surface of the front rewinding drum and up between the two drums to the rewinding shaft.

5. A rewinding machine comprising: a front and a rear rewinding drum in spaced relation, a displaceable rewinding shaft above and between said drums, a guide roller below the front rewinding drum for leading flexible material to the surface of the front rewinding drum and between the drums to the rewinding shaft, and a separator extending in between the front drum and the guide roller.

6. A rewinding machine, having an exposed front or operating side, comprising: a front and a rear rewinding drum in spaced relation, a displaceable rewinding shaft above and intermediate said drums, means for so rotating the front and rear rewinding drums in one and the same direction that their upper surfaces and the lower surface of rewound material on the rewinding shaft move in a direction toward the front side of the machine, means for guiding slit sections of material over the surface of the front rewinding drum and up between the two drums to the rewinding shaft, and slitting means adjacent the front side of the machine below the drums.

Signed at the borough of Brooklyn, in the county of Kings, city and State of New York, this 21 day of May, 1919.

JAMES A. CAMERON.
GUSTAF BERGER BIRCH.
